UNITED STATES PATENT OFFICE

PHILIP ROSENBERG AND ALBERT JAEGER, OF BROOKLYN, NEW YORK

STRAW-HAT CONSTRUCTION

Application filed September 19, 1927. Serial No. 220,400.

This invention relates to hats and has particular reference to certain improvements in men's straw hats of the type which are constructed of braids known to the trade as "flat 5 foot sennet", "improved sennet" or "split sennet", the exposed edges of the convolutions of which braids present a series of points or pointed projections as distinguished from the type of hats which are constructed of 10 plain edge braids known in the trade as "China splits" and "China fancies."

At the present time straw hats made of the first-mentioned types of braids having the points or pointed projections depend upon an 15 adhesive for securing said points or projections down upon and in contact with the next adjacent convolution. This adhesive adds considerable weight to the hat in addition to rendering the same extremely stiff, inflexible 20 and uncomfortable. Hence numerous means have been resorted to for obtaining flexibility especially at the head-receiving opening, such as employing a straw of a different character at the juncture of the portions of 25 the crown and brim.

It is therefore an object of the present invention to provide a hat constructed of a straw braid of the type which presents exposed pointed edges, which contemplates the 30 employment of a mechanical or non-adhesive means for securing down the points or pointed 35 projections in flat contact with the next adjacent convolution, whereby heavy stiff and inflexible adhesives are eliminated and a hat of a lighter and more flexible nature is produced.

More specifically the invention comprehends a straw hat constructed of a braid of the character set forth in which a mechanical 40 means, such as a line of stitching overlying the exposed points or projections, functions to secure said points or projections down in contact with the next adjacent convolution, thereby allowing a thinner, lighter and more 45 flexible adhesive to be employed.

The invention furthermore comprehends a means for securing down the exposed points or projections at the edges of the braid convolutions, which does not detract from the 50 appearance of the hat while materially in-

creasing its flexibility and decreasing its weight.

The invention furthermore contemplates a securing means which may be employed at any desired point, portion or location on the 55 hat where flexibility is desired, such as at the juncture of the brim and crown where the hat contacts with the head.

The invention furthermore aims to provide a hat construction which is simple, economical and efficient.

With the above recited and other objects in view reference is had to the following description and accompanying drawings in which there are exhibited certain examples or 65 embodiments of the invention while the appended claims define the actual scope of the invention.

In the drawings—

Figure 1 is a side view of a hat constructed 70 in accordance with the invention;

Fig. 2 is a top plan view thereof;

Fig. 3 is an enlarged fragmentary plan view of the brim illustrating the improved means for securing down exposed edges of 75 the braid convolutions;

Fig. 4 is a sectional view taken approximately on the line 4—4 of Fig. 3;

Fig. 5 is a fragmentary plan view of a portion of a hat brim illustrating a slightly 80 modified adaptation of the invention;

Fig. 6 is a sectional view therethrough taken approximately on the line 6—6 of Fig. 5.

Referring to the drawings by characters of 85 reference, 10 designates the brim and 11 the crown of a hat which is constructed as is customary, of spirally arranged and overlapping convolutions of braid 12 of the type which is provided at least at the exposed edges with 90 points or pointed projections 13. Ordinarily the braid convolutions 12 are secured in overlapped relation by a substantially concealed stitching while a heavy stiff adhesive substance is additionally employed for causing 95 the convolutions to remain in associated relation as well as to secure down the points or pointed projections 13. It is obvious that the employment of an adhesive of this character in addition to adding considerable 100

weight to the hat, is stiff and inflexible and, furthermore, the bending or distortion of the brim or crown as well as the subjection of the hat to dampness, causes the points or pointed 5 projections to turn up, thereby marring the appearance of the hat.

The present invention comprehends in lieu of employing the substantially concealed line of stitching and a heavy inflexible adhesive, 10 lines of stitching 14 which overlie and embrace the points or pointed projections 13 so that the stitching in addition to performing the function of retaining the points or pointed 15 projections down in flat contact with the next adjacent braid convolution, also serves to join or connect the adjacent braid convolutions. This eliminates the necessity of employing a 20 heavy, stiff or inflexible adhesive and allows for the use of a thin, light and flexible adhesive. It thus follows that a hat constructed 25 in this manner is light, flexible and comfortable when worn. It is furthermore obvious that due to the fact that the points or pointed 30 projections at the exposed edges of the braid convolutions are positively secured down against raising or curling up, dampness or 35 exposure to the weather does not materially affect the structure.

It is, of course, understood that within the 40 scope of the invention, the convolutions or rows of braid at any localized point or portion, such as immediately adjacent the juncture of the crown and brim, may be constructed in accordance with the invention, 45 while the remaining rows or convolutions may be treated with a stiff adhesive in the usual way. It is also apparent that where the complete brim and crown are constructed in accordance with the invention, any suitable 50 stiffening means for portions of the crown or brim may be employed.

In the modified adaptation of the invention illustrated in Figs. 5 and 6, where the rows or convolutions of braid immediately adjacent the juncture of the crown and brim are to be rendered flexible, the stitching 15 overlying and embracing the points or projections at the exposed edges of the rows or convolutions may also embrace a binding element 16 laid over or under or both over and under the brim and outside or inside or both outside and inside of the crown.

What is claimed is:

1. A straw hat having a crown portion and 55 a brim portion formed from a straw braid spirally laid in overlapped relation and joined by stitching, said braid having the outer edge thereof irregular in shape so as to provide points, the portion of the hat at the break 60 and extending for a distance into the crown and brim being substantially free from stiffening material so that the same is pliable, and a relatively narrow strip laid on the braid adjacent the points thereof throughout said 65 pliable portion, the stitching for joining the

adjacent windings of the braid being laid over said strip for securing the same to the braid for binding down the points.

2. A straw hat having a crown portion and a brim portion formed from a straw braid spirally laid in overlapped relation and joined by stitching, said braid having the outer edge thereof irregular in shape so as to provide points, the portion of the hat at the break and extending for a distance into the crown and brim being substantially free from stiffening material so that the same is pliable, and a relatively narrow strip laid across the base of the points on the face of the braid, the stitches for joining adjacent windings of the braid being passed through both windings at points adjacent the strip and the thread between consecutive stitches being laid on said strip for securing the strip and binding down the points.

3. A straw hat having a crown portion and a brim portion formed from a straw braid spirally laid in overlapped relation and bound by stitching, said braid having the outer edge thereof irregular in shape so as to provide points, the portion of the hat at the break and extending for a distance into the crown and brim being substantially free from stiffening material so that the same is pliable, a narrow strip laid on the braid adjacent the points thereof throughout said pliable portion and secured to the braid for binding down the points thereof.

Signed at the city of New York in the county of and State of New York, A. D. 1927.
